UNITED STATES PATENT OFFICE.

FRANK MANCUSO, OF BARRELVILLE, MARYLAND.

WRENCH.

1,127,269.

Specification of Letters Patent.

Patented Feb. 2, 1915.

Application filed July 24, 1912. Serial No. 711,258.

To all whom it may concern:

Be it known that I, FRANK MANCUSO, a subject of the Emperor of Italy, residing at Barrelville, in the county of Allegany and 5 State of Maryland, have invented certain new and useful Improvements in Wrenches, of which the following is a specification.

My invention relates to wrenches of the rigid jaw type and has for its object the 10 provision of means by which the wrench is adapted to use with nuts of different sizes and consists of the provision of a wrench head with a socket therein in which is slidably mounted a plurality of bars adapted 15 to be adjusted to engage the nut or to be moved into an inoperative position as desired, the bars being of different widths to provide for fitting the wrench on nuts of different sizes.

20 My invention will be described in detail hereinafter and illustrated in the accompanying drawings, in which,

Figure 1 is a top plan view of my improved wrench showing it applied to a nut, 25 with two of the bars in their outermost position, while the other bar is in its innermost position to form the jaws for the nut; Fig. 2, a longitudinal sectional view showing one of the bars partly removed from the socket; 30 Fig. 3, a cross section on the plane indicated by the line 3—3 of Fig. 2; Figs. 4 and 5, are perspective views of the clamping block.

In the drawings similar reference characters will be used to designate corresponding 35 parts throughout the several views.

My improved wrench comprises a head 1 having a socket 2 therein and two parallel jaws 3 extending from the two sides of said head, said jaws 3 being connected by means 40 of bars 4 and 5 spaced apart as shown, the spaced apart portion between the bars 4 and 5 being substantially the same width as the socket 2, as clearly shown in Fig. 2.

Mounted between the jaws 3 are a plurality of bars designated 6, 7 and 8 of different widths as shown, said bars being adapted to slide between the cross bars 4 and 5 so that they may seat in the socket 2 as shown of the bar 6 in Fig. 1, or may be moved outwardly into the position shown as to bars 7 and 8 in Fig. 1 to coöperate with one of the

jaws 3 to form the jaws of the wrench. The engaging surfaces of the bars 6, 7 and 8 adjacent to their outer terminals are milled or otherwise roughened as shown at 9 in Fig. 2 55 to assist in holding the nut in engagement therewith while the wrench is in operation. The inner surface of the cross bar 5 is formed with a recess 10 having its wall toward the socket 2 formed tapered or wedge-shape as shown at 11, and mounted in said recess 10 is a clamping member 12 having a tapered portion 13 that engages the wedge-shaped portion 11 of the recess. The clamping member 12 consists of a block as shown 60 and has sockets 14 therein in which are mounted helical springs 15 that engage the inner surface of the recess 10 and hold said block in an outwardly projected position 65 against the bars 6, 7 and 8 to prevent accidental displacement thereof from the socket 2 and from between the jaws 3. 16 indicates a threaded pin mounted in a threaded opening 17 in the cross bar 5 that engages said clamping block 12 to hold said block in a 70 clamping position against the bars 6, 7 and 8 when adjusted to be used as a wrench.

18 indicates a handle secured to the head 1 by means of a threaded shank 19 or in any other suitable manner.

Having thus described my invention what I claim is:

In a wrench, the combination with a handle, of a body portion secured thereto and having a socket formed interiorly thereof, parallel jaws extending from the two sides of said body portion, cross arms spaced and secured to said parallel arms intermediate the end and at the center thereof, slides of different sizes slidably mounted within 85 said cross arms between the parallel jaws and adapted to extend into said socket, the upper of said cross arms having a wedge-shaped recess formed in its under face, said recess tapering toward the socket aforesaid, 90 a clamping member having a flat surface and a curved surface, springs mounted upon the curved surface of said clamping member near each end thereof and said clamping member being mounted in said recess and 100 the curved surface of said clamping member registering with the curved surface of said

recess, said slides adapted to coöperate with the parallel jaws in the operation of clamping, and means for holding the clamping member into engagement with said slides 5 including a screw mounted in the upper cross arm and engaging said clamping member.

Copies of this patent may be obtained for five cents each, by addressing the "Commissioner of Patents, Washington, D. C."

In testimony whereof I affix my signature in presence of two witnesses.

FRANK MANCUSO.
